UNITED STATES PATENT OFFICE.

ARTHUR H. ARMSTRONG, OF NEW YORK, N. Y.

EGG-CARRIER.

1,239,661.

Specification of Letters Patent.

Patented Sept. 11, 1917.

Application filed May 12, 1915. Serial No. 27,688.

To all whom it may concern:

Be it known that I, ARTHUR H. ARMSTRONG, a citizen of the United States, residing at New York, in the county of New York and State of New York, have invented a new and useful Improvement in Egg-Carriers; and I do hereby declare the following, when taken in connection with the accompanying drawings and the characters of reference marked thereon, to be a full, clear, and exact description of the same, and which said drawings constitute part of this application, and represent, in—

Fig. 1 a side view partly in section of an egg carrier constructed in accordance with my invention.

Fig. 2 a broken top view of the same.

Fig. 3 a broken side view illustrating a modified form of egg support embodying my invention.

Fig. 4 a plan view of a portion of the supporting sheet shown in Fig. 3.

Fig. 5 a broken plan view of another modified form of supporting member.

Fig. 6 an edge view of the same.

This invention relates to an improvement in egg carriers and particularly to carriers which comprise sections or tiers of sections formed by paper partitions, the object being to provide a cheap and efficient resilient support for eggs as they are packed in cases for transportation, and I accomplish this object by the construction and arrangement of parts as hereinafter described and illustrated in the accompanying drawings, the novel features of my invention being pointed out in the annexed claims.

The egg carrier case to which my invention is applied, is constructed of the usual form, comprising an outer box 1 of sufficient strength and rigidity to withstand the rough usage incident to transportation, and containing a series of cardboard partitions 2 forming rectangular cells of the proper size to receive an egg, as shown at 3, Fig. 1. In Fig. 1 I have shown a case containing two tiers of cells, one superimposed upon the other, and separated by a partition embodying my present invention and providing a contacting surface for the ends of eggs contained in the cells. I also provide similar resilient supports placed upon the bottom 4 of the egg case and also beneath the top or cover 5.

I am aware that it has been proposed to provide resilient supports for eggs in trans-

portation by means of metal springs arranged to bear against the ends of the egg; also that it has been proposed to employ a cushion of some suitable material, such as 60 felt. The use of springs is expensive. They render the cases bulky owing to the space they require to form an efficient cushion, and difficulty is experienced in maintaining the proper contact with the egg so that the pressure of the spring is applied in an axial line. A cushion of felt by long continued use becomes matted by compression and loses its 65 resilient character. It is the object of my present invention to provide an efficient 70 cushion for the egg requiring but little room in the case, and so inexpensive that, if discarded or lost, the cost of replacement will be negligible.

In carrying my invention into practice, I 75 preferably place upon the bottom of the case a sheet of cardboard 6 fitting the interior of the case. Upon this I place a second sheet of cardboard 7, in which I form a series of raised elastic prongs 8 arranged 80 about a common center and registering with each of the egg cells formed by the partitions 2. Each set of elastic prongs forms an individual cushion contacting with the end of the egg contained in the egg cell. Each 85 group of elastic prongs 8 is formed, in the present instance, by cutting eight slits, Fig. 2, forming eight triangular prongs 8 with their apices converging. The cardboard in a moistened state is then molded between 90 suitable dies by which four of the triangular prongs 8 are raised and four depressed, forming upon each prong a beveled section 10 and a horizontal tip 11, as shown in sectional view in Fig. 1. The cardboard from 95 which the elastic prongs 8 are molded is of suitable texture to give suitable resiliency to the prongs so that, as they are bent by the pressure of the egg upon their tips, as shown at 12, 12, Fig. 1, they will return to 100 their original form when the pressure is removed. The construction of the cushions at the bottom of the box, as above described, is duplicated at the top of the box.

In order to separate the successive tiers of 105 egg cells, I employ a similar sheet, and preferably these sheets will have a central bar 13 between the prongs as shown in Fig. 2 of the drawings, which bar prevents the deformation of the material at the base of the 110 deflected portions. By the use of cardboard having the proper resilient quality when

molded as above described, the tips 11 of the prongs 8, Fig. 2, will possess sufficient resiliency to form an elastic support for the egg sufficient to prevent breakage during any jar or concussion imparted to the case. The prongs will also possess sufficient resiliency, if cardboard of the proper character is employed, to serve the purpose of cushions for long continued use. In the molded form of the prongs 8, while in a moistened state, the cardboard becomes stretched, and when again dried the original elasticity of the cardboard is not only restored but is increased, due to the raised form of the prongs.

In Figs. 1 and 2 I have illustrated, and described above, one form of constructing the elastic prongs by which my invention is carried into effect. I do not confine myself, however, to the specific details of construction as above described, as various modifications may be adopted without departing from the spirit of my invention. One of these modifications I have illustrated in Figs. 3 and 4, which consists in the use of a central sheet of cardboard 16, over one edge of which a sheet 17 is folded. The sheet 17 is double the size of the sheet 16 and has a double series of groups of elastic prongs forming cushions for two adjacent tiers of egg cells, the prongs 18 forming a contacting surface for the eggs in the lower tier and the prongs 19 for the eggs in the upper tier. Another modification shown in Figs. 5 and 6 consists in attaching to a sheet of cardboard 20 strips of elastic cardboard 21 having intersecting slits 22. The points of intersection of the slits 22 are arranged to register with the center of the egg cells in the case, and the strips 21 are glued to the sheet 20 and bent at right angles at 23, 24, to bring the horizontal sections 25 containing the slits 22 above the sheet 20, in order to provide a space for the deflection of the triangular sections or prongs formed by the slits 22 without their contacting with the sheet 20, which limits the movement of the

prongs and thereby the movement of the eggs. These sheets 20 with the superimposed strips 21 are placed one below and one above each layer of eggs, the upper sheet being reversed so that the ends of the eggs are supported by the prongs formed by the slits 22. The sheet 20 limits the deflection of the prongs and the movements of the eggs. By the above described method of construction I produce a series of elastic triangular prongs by means of the slits 22, capable of yielding to the pressure of the egg without the expense of molding the sheet as shown in Figs. 1 and 2.

While I have shown and described the egg supporting devices of my invention as made of cardboard, it is obvious that any equivalent material may be employed therefor, such, for instance, as vulcanized fiber.

I claim:

1. In an egg carrier comprising an egg cell, a sheet material egg-supporting member formed with prongs deflected out of the plane of the said sheet and into said cell, the points of the prongs providing a resilient support for the egg, and means for limiting the movement of the said prongs.

2. In an egg carrier, an egg supporting member formed from a sheet of material folded upon itself the upper fold of said member having portions thereof deflected above the plane of the sheet and the lower fold having portions deflected below the plane of the said sheet, whereby resilient supports are formed on each side of said member, and a central sheet between the folds to limit the deflected portions.

3. In an egg carrier, the combination with a series of egg cells arranged one above the other, of a supporting member formed from sheet material, said member having portions thereof deflected above and below the plane of said member, said deflected portions projecting into adjacent cells, and means for preventing deformation of the sheet at the base of the said deflected portions.

ARTHUR H. ARMSTRONG.
